UNITED STATES PATENT OFFICE.

ALFRED S. McCASKEY, OF CHICAGO, ILLINOIS.

FLEXIBLE SHAFT.

1.314.601.

Specification of Letters Patent. Patented Sept. 2, 1919.

Application filed January 10, 1919. Serial No. 270,467.

To all whom it may concern:

Be it known that I, ALFRED S. McCASKEY, a citizen of the United States, and a resident of Chicago, in the county of Cook and State of Illinois, have invented certain new and useful Improvements in Flexible Shafts; and I do hereby declare that the following is a full, clear, and exact description thereof, reference being had to the accompanying drawings, and to the letters of reference marked thereon, which form a part of this specification.

This invention relates to improvements in flexible shafts and consists of the matters hereinafter described and more particularly pointed out in the appended claims.

In flexible shafts of that type wherein each shaft unit is made with a bearing notch in one end and a projecting lug at the other 20 adapted to engage the corresponding bearing notch of an adjoining unit in such manner as to permit of flexibility between the engaged shaft units, it has been found desirable heretofore to use means for retaining the 25 units in their assembled relation. For example, Letters Patent No. 1,258,233 dated March 5, 1918, illustrates this type of shaft, in which the units were tubular and wherein it was found necessary to employ rings 30 within the units to retain the lugs within the bearing notches.

In other instances, it has been found desirable to employ a mandrel within the tubular units for the same purpose. Such retaining mandrel may be, for example, a coiled spring or a flexible body such as a hose or metal tube which would usually extend longitudinally of the shaft through several units.

40 The principal object of my invention is to eliminate all extra locking parts or devices in flexible shafts composed of inter-engaging shaft units of the general type above referred to, and to accomplish the locking of
45 the assembled units by means integral with the unit. This may be accomplished not only in that type of flexible shaft wherein the units are of cast or forged tubular form, as well as with those units stamped out of a
50 blank and fashioned in tubular form, but also with units formed of rods or other solid metal. The integral locking means may be employed in various ways. For example, in the sheet metal type, the locking agency may
55 be created when the blank is stamped out and may be brought into action as and when

the blank is fashioned in tubular form. In the case of cast or forged tubular units or units cut out of solid metal, the locking agency may be created and brought into action as part of the shaft assembly operation. Again, in the case of a tubular unit, the locking agency may consist of integral projections or protuberances created when the unit is formed and which, after two units are assembled, may be bent into a different position to engage opposite sides of the adjoining unit. 60 65

The object of the invention is to provide a flexible shaft, which is cheap to manufacture, easy to assemble, efficient in operation for its intended purpose, and which is strong and durable, thus insuring greater amount of service than has heretofore been attainable in flexible shafts as now made. 75

Other objects and advantages will appear as I proceed with my specification.

In the drawings:

Figure 1 is a view in side elevation of one form of my improved flexible shaft as it appears within its sheath or covering. 80

Fig. 2 is a view of a portion of this same shaft, showing two adjoining units without the sheath or covering.

Fig. 3 is a view on a somewhat enlarged scale showing one unit of a flexible shaft made in accordance with this same form of my invention. 85

Fig. 4 is a transverse sectional view through two adjoining units of this same form of my improved flexible shaft, the plane of the section being indicated by the line 4-4 of Fig. 2.

Fig. 5 is a perspective view on an enlarged scale of one of the units or links of a modification of my improved flexible shaft. 95

Fig. 6 is a sectional view similar to that of Fig. 4 showing two adjoining units of the modified form illustrated in Fig. 5.

Figs. 7 and 8 are views similar to those of Figs. 3 and 2 respectively, but illustrating my invention applied to units formed of solid metal.

Figs. 9, 10 and 11 illustrate yet another embodiment of the invention, wherein the 105 units are made of sheet metal bent into tubular form.

Fig. 12 is a plan view of a blank from which the unit illustrated in Figs. 9, 10 and 11 may be made.

Referring now to that embodiment of my invention as illustrated in the drawings and

more particularly to that form shown in Figs. 1 to 4 inclusive thereof, A indicates, as a whole, a short section or length of my improved flexible shaft, comprising a plurality of substantially short, tubular units or links 1 which are coupled or connected together in a manner preventing relative displacement in any direction between them, while at the same time permitting a desirable range of flexible movement between each adjoining unit. Each unit or link has a body part 2 which is preferably made of a length approximating its diameter. This proportion could be materially changed 15 without departing from the spirit of the invention.

The body 2 of each unit 1 is provided at one end with a pair of longitudinally extending, diametrically opposite lugs 3, 3, 20 and at its other end with complementary shaped, bearing notches 4, in which the lugs 3, 3, of an adjoining unit are adapted to engage in a manner coupling said units together. The diametric plane of the lugs 3 25 of one unit is arranged at right angles to the corresponding plane of the bearing notches 4 in the same unit. The advantage of such an arrangement is manifest.

Each lug 3 consists of a head 5 which is 30 connected to the end of the associated body 2 by means of a neck 6, the lateral edges of which diverge outwardly as they approach said body. Each bearing notch 4, formed in the opposite end of said body is of a concave 35 tour corresponding to and adapting it to receive the lugs 3 of an adjoining unit. Each bearing notch 4 opens into the free end of said body by means of a somewhat restricted passage or throat 7, through which the neck 40 6 of an associated lug 3 extends when said units are coupled or connected together.

As shown in Fig. 1, the left-hand, endmost unit 1 is coupled or connected by means of its lugs 3 in bearing notches 8 (which are 45 identical to the bearing notches 4, before mentioned), formed in a terminal unit 9. Said terminal unit may be either a tool holding chuck or the like or it may constitute a coupling connection with a suitably 50 driven member.

10 indicates a suitable sheath or covering for the shaft which may comprise an inner metallic member of coiled wire 11 and an outer member of flexible material 12, such as 55 rubber or textile tubing. A collar 13 is fixed to the terminal end of said sheath, and a bearing ring 14 is placed within said collar to provide the proper bearing for the terminal unit 9.

60 To prevent any tendency of the several coupled together or connected units to pinch or cut into the sheathing and to prevent binding between the adjoining ends of the several units, especially when the shaft as a 65 whole is arranged on a curve or arc, it is

desirable to round off the sharp edge at the ends of the body of each unit as indicated at 15, 15, in Figs. 2 and 3.

At 16 is indicated a recess extending part way around the inner part of the bearing notch 4 and 17 is a small projection extending outwardly from the lug 3. These projections and recesses 17, 16 are complementary and serve to bind or lock adjacent units. That is to say, the projections 17 hold the lugs 3 within the notches 4. The recess 16, being much longer than the width of the projection 17, affords a desirable range of flexibility of movement between said locked units. I prefer to construct the recess 16 and the projections 17 by a suitable mechanism after the units are constructed, and as part of the shaft assembling operation. That is to say, the units 1 are first made without the recesses 16 and projections 17, and two units 35 are then assembled by placing the lugs 3 of one unit within the bearing notches 4 of the next unit, and then the two units so assembled are subjected to the action of a suitable press which forms the recess 16 and then 40 acts upon the lugs 3 and forces out sufficient of its metal to form the projection 17. Manifestly, the only way to disassemble the units thus flexibly locked together is to physically remove one of the projections 17 from 45 its lug 3.

In the form of my invention illustrated in Figs. 5 and 6, the units 1 are also tubular in form, and correspond in every particular with the units shown in Figs. 1 and 4 inclusive, just described, with this exception, namely: that instead of subjecting the assembled units to the action of a suitable machine to form the recesses 16 and projections 17, there are no such recesses, and in lieu of 105 the projections 17 of the first form, I construct on each lug 3 a downwardly and inwardly directed projection or lug 18 as clearly seen in Fig. 5. When the units having projections 18 are assembled, said projections are bent forwardly in prolongation of the lugs 3 and extend under and against the inner surface of the bearing notches 4, as clearly disclosed in Fig. 6, thus forming 110 interlocking shoulders 19 and preventing the 115 disassembly of the units.

In that form illustrated in Figs. 7 and 8, the units 21 are made from solid metal, such for example as a rod. Each unit has a cylindric body 22, a longitudinally extending projecting lug 23 extending across one end, and at its other end a complementary shaped bearing notch 24 in which the lug 23 of the adjoining unit is adapted to engage, as will be manifest from the drawings, the 120 diametric plane of the lug 23 being arranged at right angles to the corresponding plane of the notch 24.

When the units 21 are being assembled, a suitable press may form recesses 25, 26 on 130

opposite sides of the body 22 at the outer edges of the bearing notches 24, (similar to the recess 16 of Fig. 2), and also press out 5 the lug 23, said projections 27 being narrower than the length of the recesses 25, 26, and adapted to engage them as illustrated in Fig. 8, to lock two adjoining and assembled units 21, 21 from disengagement.

10 In the form shown in Figs. 9 to 12 inclusive, B represents a sheet metal blank provided along one side margin *a* with two projections *b*, *b*. The opposite side margin *c* is cut away to form a recess *d* complementary 15 in shape with that of the projection *b* so that the latter may have bearing in a similar recess when the blank is folded into tubular form. There being two projections *b*, on the margin *a* it follows that on the opposite 20 side *c*, there will be one recess *d* and two half recesses *d'*, *d'*. The diametric plane of the recesses *d* and *d'*, when the blank is folded into tubular form, will be at right angles to the corresponding plane of the projections *b* in the same unit.

25 The margin of the two projections *b*, *b*, on the same side of the blank B, are beveled off at *e* to constitute, in effect, a projecting or overlapping part of the projections *b*, *b*. The corresponding margins of the recesses 30 *d*, *d'*, on the opposite side of the blank are similarly beveled at *f*, the latter being indicated by dotted lines in Fig. 12. It follows that when the blank B is bent up to 35 form a tubular unit, as C, and a second blank then similarly formed, in juxtaposition to the formed unit C, as indicated at D, not only will the projections *b*, *b*, of the unit D properly engage the recesses *d* and *d'* of the unit C, but the beveled overlapping portions *e* of the unit D will have locking bearing 40 engagement with the beveled portions *f* of the unit C and thus prevent the disassociation of the units C and D.

45 Thus it will appear that whether the proximate surfaces or margins of adjoining units are fashioned before or during or as a part of the shaft-assembling operation, provision is made for projecting lugs on one 50 unit to flexibly engage bearing notches in the adjoining unit, to form the shaft, and that coöperating means, integral with each unit, is provided to lock the units in flexible relation and prevent disassembly.

55 While in describing my invention I have referred to certain details of mechanical construction and arrangement of parts, I do not wish to be limited thereto except as may be pointed out in the appended claims.

60 I claim as my invention:

1. A flexible shaft comprising a plurality of units, each of said units comprising a body part having at one end diametrically opposite bearing notches and at its other end longitudinally extending, diametrically op-

posite bearing lugs arranged at right angles to said notches, said lugs being adapted to engage within the bearing notches of the adjoining unit in a manner permitting of a flexible movement between said units, and integral means for operatively retaining the lugs within said bearing notches. 70

2. A flexible shaft comprising a plurality of units, each of said units comprising a tubular body part having at one end diametrically opposite bearing notches and at its other end longitudinally extending, diametrically opposite bearing lugs arranged at right angles to said notches, said lugs being adapted to engage within the bearing notches of the adjoining unit in a manner permitting of a flexible movement between said units, and integral means for operatively retaining the lugs within said bearing notches. 75

3. A flexible shaft comprising a plurality of units, each of said units comprising a body part having at one end diametrically opposite bearing notches and at its other end longitudinally extending diametrically opposite bearing lugs arranged at right angles to said notches, said lugs being adapted to engage within the bearing notches of the adjoining unit in a manner permitting of a flexible movement between said units, and integral means for operatively retaining the lugs within said bearing notches. 80

4. A flexible shaft comprising a plurality of units, each of said units comprising a tubular body part having at one end diametrically opposite bearing notches and at its other end longitudinally extending, diametrically opposite bearing lugs arranged at right angles to said notches, said lugs being adapted to engage within the bearing notches of the adjoining unit in a manner permitting of a flexible movement between said units, and integral means for interlocking the margin of the lug and the corresponding part of its notch to retain the lug therein. 90

100

5. A flexible shaft comprising a plurality of units, each of said units comprising a body part having at one end diametrically opposite bearing notches and at its other end longitudinally extending, diametrically opposite bearing lugs arranged at right angles to said notches, said lugs being adapted to engage within the bearing notches of the adjoining unit in a manner permitting of a flexible movement between said units, and integral means for operatively retaining the lugs within said bearing notches, said means comprising complementary interlocking means 110 on the lugs and notches. 115

6. A flexible shaft comprising a plurality of units, each of said units comprising a tubular body part having at one end diametrically opposite bearing notches and at 130

its other end longitudinally extending diametrically opposite bearing lugs arranged at right angles to said notches, said lugs being adapted to engage within the bearing notches 5 of the adjoining unit in a manner permitting of a flexible movement between said units, and integral means for operatively retaining the lugs within said bearing notches, said means comprising complementary interlocking means on the lugs and notches.

7. A flexible shaft comprising a plurality of units, each of said units comprising a body part having at one end diametrically opposite bearing notches and at its other end longitudinally extending diametrically opposite bearing lugs arranged at right angles to said notches, said lugs being adapted to engage within the bearing notches of the adjoining unit in a manner permitting of a flexible movement between said units, and integral means for operatively retaining the lugs within said bearing notches, said means including a projection on each lug adapted 20 for locking engagement with the unit body adjacent the lug recess.

8. A flexible shaft comprising a plurality of units, each of said units comprising a tubular body part having at one end diametrically opposite bearing notches and at its other end longitudinally extending diametrically opposite bearing lugs arranged at right angles to said notches, said lugs being adapted to engage within the bearing notches 30 of the adjoining unit in a manner permitting of a flexible movement between said units, and integral means for operatively retaining the lugs within said bearing notches, said means including a projection on each lug adapted for locking engagement with the unit body adjacent the lug recess.

9. A flexible shaft comprising a plurality of units, each of said units comprising a body part having at one end diametrically opposite bearing notches and at its other end longitudinally extending diametrically opposite bearing lugs arranged at right angles to said notches, said lugs being adapted to engage within the bearing notches of the adjoining unit in a manner permitting of a flexible movement between said units, and integral means for operatively retaining the lugs within said bearing notches, said means including interiorly and inwardly directed, 45 locking projections on the lugs adapted to be bent outwardly to project beyond the margin of the lug and engage the adjacent link unit body.

10. A flexible shaft comprising a plurality of units, each of said units comprising a tabular body part having at one end diametrically opposite bearing notches and at its other end longitudinally extending diametrically opposite bearing lugs arranged 60 at right angles to said notches, said lugs be-

ing adapted to engage within the bearing notches of the adjoining unit in a manner permitting of a flexible movement between said units, and integral means for operatively retaining the lugs within said bearing 70 notches, said means including interiorly and inwardly directed, locking projections on the lugs adapted to be bent outwardly to project beyond the margin of the lug and engage the adjacent link unit body.

11. A flexible shaft comprising a plurality of units, each of said units comprising a body part having at one end diametrically opposite bearing notches and at its other end longitudinally extending diametrically opposite bearing lugs arranged at right angles to said notches, said lugs being adapted to engage within the bearing notches of the adjoining unit in a manner permitting of flexible movement between said units, diametrically opposite or cut away portions or depressions in the body of each unit adjacent to the bearing notches, and complementary means on each lug adapted to operatively engage said depressions.

12. A flexible shaft comprising a plurality of units, each of said units comprising a tubular body part having at one end diametrically opposite bearing notches and at its other end longitudinally extending diametrically opposite bearing lugs arranged at right angles to said notches, said lugs being adapted to engage within the bearing notches of the adjoining unit in a manner permitting of flexible movement between said units, 95 diametrically opposite or cut away portions or depressions in the body of each unit adjacent to the bearing notches, and complementary means on each lug adapted to operatively engage said depressions.

13. A flexible shaft comprising a plurality of units, each of said units comprising a body part having at one end diametrically opposite bearing notches and at its other end longitudinally extending diametrically opposite bearing lugs arranged at right angles to said notches, said lugs being adapted to engage within the bearing notches of the adjoining unit in a manner permitting of a flexible movement between said units, and means on each unit arranged to overlap the adjacent part of the next unit in the shaft to retain the units against displacement after being assembled.

14. A flexible shaft comprising a plurality of units, each of said units comprising a tubular body part having at one end diametrically opposite bearing notches and at its other end longitudinally extending diametrically opposite bearing lugs arranged at right angles to said notches, said lugs being adapted to engage within the bearing notches of the adjoining unit in a manner permitting of a flexible movement between said units, and means on each unit arranged to 120 125 130

overlap the adjacent part of the next unit in the shaft to retain the units against displacement after being assembled.

15. A flexible shaft comprising a plurality of units made from sheet metal blanks, each blank when folded into tubular form comprising a body part having at one end diametrically opposite bearing notches, and at its other end longitudinally extending, diametrically opposite bearing lugs arranged at right angles to said notches, the lugs being adapted to engage the bearing notches of an adjoining unit in a manner to permit

of flexible movement between said units, and integral, complementary locking means on 15 said lugs and notches to retain the lugs in said notches.

In testimony, that I claim the foregoing as my invention I affix my signature in the presence of two witnesses, this 4th day of 20 January, A. D. 1919.

ALFRED S. McCASKEY.
